UNITED STATES PATENT OFFICE.

JOSEPH A. AGRILLO, OF ROCKAWAY BEACH, NEW YORK.

REFRIGERATOR.

No. 870,532.

Specification of Letters Patent.

Patented Nov. 12, 1907.

Application filed March 2, 1907. Serial No. 360,164.

To all whom it may concern:

Be it known that I, JOSEPH A. AGRILLO, a citizen of the United States, and residing at Rockaway Beach, in the county of Queens and State of New York, have 5 invented certain new and useful Improvements in Refrigerators, of which the following is a specification, such as will enable those skilled in the art to which it appertains to make and use the same.

This invention relates to refrigerators of the class 10 used in dwellings, restaurants, hotels and similar places, and the object thereof is to provide an improved device of this class which is box-shaped in form and which is made up of separate panels comprising frames filled in with concrete, whereby a strong and substantial structure 15 is provided and by means of which a low temperature may be maintained within the refrigerator at a minimum of cost.

The invention is fully disclosed in the following 20 specification, of which the accompanying drawing forms a part, in which the separate parts of my improvement are designated by suitable reference characters in each of the views, and in which:

Figure 1 is a perspective view of a refrigerator made according to my invention; Fig. 2 a vertical section on the 25 line 2—2 of Fig. 1; Fig. 3 a partial section on the line 3—3 of Fig. 2; Fig. 4 a plan view of a number of the panels which I employ in the construction of a side wall of my improved refrigerator and showing one method of connecting said panels; Fig. 5 a side view of 30 the construction shown in Fig. 4; Fig. 6 a face view of a corner frame which I employ; Fig. 7 a side view of one of the side panel frames which I employ; Fig. 8 a transverse section on the line 8—8 of Fig. 7; and, Fig. 9 a transverse section on the line 9—9 of Fig. 6.

35 In the drawing forming part of this specification, I have shown a refrigerator composed of three compartments arranged one above another, but my invention is not limited to a refrigerator of any definite size or containing any definite number of compartments and 40 the same may be applied in the construction of a refrigerator containing but one or any number of compartments.

By reference to Figs. 1 and 2, it will be seen that my 45 improved refrigerator as shown comprises a bottom compartment *a*, a central compartment *b* and a top compartment *c*, the said compartments being separated by horizontal partitions *d*, and the said refrigerator is provided with a top *e* and bottom *f*. The front, back and side walls of all of the compartments *a*, *b* and 50 *c* are of the same construction and are composed of hollow corner frames *g* filled in with concrete as shown at *g*² and front, back and side panel frames *h* filled in with concrete as shown at *h*², and in the form of construction shown, two different styles of these panel frames are 55 employed, but in practice a single style of panel frame may be employed for forming the front, back and side

walls of each of the compartments *a*, *b* and *c* and a single style of corner frame *g* may be employed for forming all of the corners. The top *e* and bottom *f* of the refrigerator are also composed of separate panel frames *e*² and *f*² 60 respectively, and these panel frames are filled in with concrete as shown at *e*³ and *f*³. The front, back and side panel frames of the separate compartments *a*, *b* and *c* and the corner frames *g* are interlocked as shown at *h*³, and the partitions *d* and the front, back and side 65 panel frames of the separate compartments are interlocked as shown at *h*⁴, and said partitions, panels and frames are all bolted together, as clearly shown in Figs. 1, 2 and 3.

In Figs. 6 and 9, I have shown one of the corner 70 frames in detail and in Figs. 7 and 8 one of the side panel frames in detail, but my invention is not limited to any particular form or construction of these frames nor to any particular form or construction of the top *e*, bottom *f* and partitions *d*, all that is necessary in this 75 connection being that said parts be composed of open-work frames filled in with concrete, and these frames may be provided as shown at *i*, in Figs. 4 and 5, with reinforcing material consisting of interwoven wires or rods or any other suitable material usually employed 80 to reinforce concrete work.

Within one part of the top compartment *e* is placed 85 an ice pan *j*, and said compartment may be provided in either side or in the front with a door through which ice may be passed into said pan, and, in the form of construction shown, the top compartment is also provided with a plurality of front doors *c*² by which easy 90 access may be had to the various parts of said compartment and these doors may also be composed of frames filled in with concrete. The central compartment *b* is also provided in the front thereof with two doors *b*² and these doors may be ordinary hinge doors or doors which move out at the bottom and slide in at the top in the ordinary manner, and said doors may be composed of panel frames filled in with concrete or 95 provided with glass panels. The bottom compartment *a* is also provided with a door *a*² which may be made in the same manner as the panels which form the front, back and side walls of said compartments, and between the bottom and middle compartments is preferably placed a shelf *k* and in one side portion of the middle compartment, preferably the left hand side portion, is placed a water tank *k*² provided at its front 100 end with a pipe *k*³ which extends through the top front wall of said compartment and is provided with a faucet *k*⁴.

The ice pan *j* is provided with a drain pipe *j*² which extends downwardly through the refrigerator and opens in the bottom thereof in the usual manner, and said refrigerator is preferably provided at the top with a 110 molding *j*³ and at the bottom with a base molding or similar construction *j*⁴.

In filling the various panel frames, corner frames, partition frames and other frames with concrete, a suitable mold box is provided in which said frames are placed and the concrete is poured into the mold box 5 so that it exactly fills the frames and when the concrete has set or become hard the mold box is opened up and the panel or other frame or frames taken out.

Although, I have clearly shown the method of connecting the top and bottom frames, the partitions, the corner frames and the panels which make up the front, back and side walls of the separate compartments and have also shown a corner frame and a panel frame of specific construction, it will be apparent that my invention is not limited to any particular form or forms 15 for these various frames, and changes in and modifications of the construction herein described may be made without departing from the spirit of my invention or sacrificing its advantages. It will also be understood that the various compartments of the refrigerator shown 20 and described may be used as receptacles for any kind or class of articles, and by making the walls of the refrigerator in the manner described, I am enabled to retain a low temperature therein with the use of a minimum amount of ice.

The concrete reinforcing material shown in Figs. 2, 25 3, 4 and 5 is not necessary in most cases as the panel or other frames will be so small and the concrete employed so thick that the latter will possess the necessary strength without the use of reinforcing material but in some cases it may be required to use said reinforcing 30 material.

Having fully described my invention, what I claim as new and desire to secure by Letters Patent, is:—

A refrigerator divided into separate compartments one above another, said refrigerator being composed of front, 35 back and side walls and of a top, a bottom, and horizontal partitions by which the refrigerator is divided into separate compartments one above another, said front, side and back walls, the top, the bottom and horizontal partitions being all composed of frames filled in with concrete, and corner frames also filled in with concrete, all of said frames being provided with interlocking means whereby they may be secured together by means of bolts passed therethrough.

In testimony that I claim the foregoing as my invention I have signed my name in presence of the subscribing witnesses this 28th day of February 1907.

JOSEPH A. AGRILLO.
